UNITED STATES PATENT OFFICE.

JOHN ALGER DAHLSTROM, OF EAST CLEVELAND, OHIO, ASSIGNOR TO PERFECTION STOVE COMPANY, OF CLEVELAND, OHIO, A CORPORATION OF OHIO.

DESIGN FOR A BURNER.

Application filed December 3, 1926. Serial No. 19,912. Term of patent 14 years.

To all whom it may concern:

Be it known that I, JOHN ALGER DAHLSTROM, a citizen of the United States, residing at East Cleveland, in the county of Cuyahoga and State of Ohio, have invented a new, original, and ornamental Design for Burners, of which the following is a specification, reference being had to the accompanying drawing forming part thereof, wherein—

Fig. 1 is a plan view, and Fig. 2 a side elevation, of a burner showing my new design.

I claim:

The ornamental design for a burner as shown.

JOHN ALGER DAHLSTROM.
